UNITED STATES PATENT OFFICE.

CHARLES E. FARRINGTON, OF PHOENIXVILLE, PENNSYLVANIA.

AGITATOR AND LOCK THEREFOR.

Application filed January 23, 1924. Serial No. 637,966.

To all whom it may concern:

Be it known that I, CHARLES E. FARRINGTON, a citizen of the United States, residing at Phoenixville, in the county of Chester 5 and State of Pennsylvania, have invented new and useful Improvements in Agitators and Locks Therefor, of which the following is a specification.

This invention has relation to devices for 10 stirring or agitating the contents of a tank, barrel or other closed receptacle such as exemplified in Letters Patent of the United States No. 1,836,830, granted to me on the 13th day of April, 1920.

15 The object of the present invention is to provide means for effecting the operation of the agitator blade, which means may also serve as a closure for the opening in the barrel or receptacle; to provide a lock for 20 said means; and also to provide an effective device for securing an operating handle to the tank or closure for shipment therewith. The manner in which the objects are attained and an embodiment of the invention 25 are herein illustrated and described and particularized in the claims appended hereto.

On the drawings,—

30 Figure 1 illustrates in section a portion of a container equipped with one embodiment of the invention, the parts with the exception of the stirrer blade and the handle being shown in section.

35 Figure 2 represents a perspective view of a bung or closure which performs the function of closing an aperture in the container and of transmitting power to the agitator or stirrer blade.

40 Figure 3 represents a locking device by which the bung or closure is held against rotation and an operating handle is secured to the container.

45 Figure 4 represents a handle which may be employed for rotating the bung or closure.

Figure 5 represents a perspective view of the container with the parts locked ready for shipment.

50 Before describing in detail the devices which are illustrated by the figures thus briefly referred to, I desire to have it understood that these devices constitute but one embodiment of the invention and that the invention is capable of various other embodi-

ments without departing from the spirit 55 and scope thereof as expressed in the claims.

In Figures 1 and 5, I have conventionally illustrated at 10 a container which may take the form of steel or other metal drum or barrel having a head 11. This drum or barrel 60 may be of any convenient shape or form and may be made of any suitable material. It is provided with a central aperture through which a stirrer blade such as indicated at 12 65 may be introduced, and this stirrer blade may be of the form and shape and may function as set forth in the said Letters Patent hereinbefore referred to. It will, of course, be understood that there may be used in lieu thereof any other suitable form of agitator 70 or stirrer which may be found to be desirable for the purpose of mixing, stirring or agitating the contents of the container. The head of the container is provided with an internally-threaded aperture 13. If the head 75 of the container is of relatively thin metal, this threaded aperture may be formed in a metallic annulus or ring 14 placed in a suitable aperture formed in the head 11 and secured thereto by any suitable means as by welding, brazing or the like. In such latter case, the ring is of sufficient length axially 80 to provide a threaded portion sufficient for firm threaded engagement therewith of the bung, closure or coupling member by which power is transmitted to the stirrer blade for the operation thereof. This element in the present instance may take the form of a substantially cylindrical member 15 having an 85 external threaded portion 16 which may be screwed into the threaded aperture in the container. On its inner or lower end said member 15 is provided with two jaws 17 for 90 engaging the upper end of the stirrer blade 12. These jaws form a socket into which the end of the stirrer blade projects, and it is of course apparent that the socket may be otherwise made so as to permit of a sliding engagement between the stirrer blade 95 and the member, and at the same time to permit the rotation of the stirrer blade when the said member itself is rotated. Preferably the threads are so formed on the member 15 and in the wall of the aperture in the container head that the clockwise rotation 100 of the said member 15 withdraws it or moves it outward from the aperture to a position as shown in Figure 1, whereupon the con-

tinued rotation of the said member merely effects the rotation of the stirrer blade. If desired, the said member 15 may be provided with a non-threaded portion 18, which, when 5 its threaded portion is out of engagement with the threads of the aperture, may extend into said aperture so as to steady the member during its rotation.

For the purpose of effecting the rotation 10 of the operating coupling member or bung 15, any suitable handle may be employed. I have shown, for example, a handle comprising a bar 19 having at one end the lugs 20, 20 like those of a spanner which may 15 be introduced or inserted into apertures 21, 21 formed in the head or outer portion of the member 15. At its other end the bar is provided with a crank 22, which if desired may be equipped with a rotatable sleeve 23.

20 Inasmuch as the member 15 and the handle may be easily detached, it is desirable to provide some means for locking them so that the container and the member just described may be shipped as a unit. For 25 this purpose, I may employ a locking ring as illustrated in Figure 3 and as indicated at 24. This locking ring is preferably formed of some suitable relatively-ductile metal provided with a series of lugs 25, 25, 25, 26. 30 One or more of these lugs may be interlocked with the bung or coupling member 15 and the other with the head of the container. Of course the number of the locking lugs is immaterial, two being sufficient 35 for the purpose. For example one of the lugs as at 26 may be forcibly bent so as to extend into a socket 27 formed in any suitable way in the head of the container, whereas another of the lugs may be forcibly 40 bent upwardly so as to extend in any one of a series of notches 28 formed in a peripheral flange 29 on the head end of the coupling member 15. Preferably the lugs 25 are unequally spaced, whereas the notches 28 are 45 equally spaced; so that, in screwing the coupling member home into the threaded aperture in the head of the container, one of these notches may be brought into alignment with one of the lugs 25 and the lug then 50 bent into or lie in the notch which registers therewith. The ring itself may serve as a gasket, or, if desired, a suitable thin gasket 55 may be placed between the ring 24 and the head of the container,—in this case the annulus 14.

In order that the handle may be secured 60 to the container, the ring 24 may be provided with an extension 30 which is so curved, as shown in the drawings, as to extend over the body of the handle and clamp it firmly against the container head 11. In Figure 5, the container is shown ready for 65 shipment, the handle being clamped against the head thereof and the coupling member being locked to the head all by means of the

ring member 24. The person receiving the tank, by a suitable implement such for example as a screw driver or cold chisel, may bend the lug 26 out of engagement with the socket 27 and bend the locking lug 25 out of engagement with its complementary notch 28; and then, either by means of a spanner 70 rotate the coupling member 15 anti-clockwise so as to release the handle 19 or by the implement previously used by him bend the 75 clamping member 30 sufficiently to release the handle, whereupon the handle itself may be employed in rotating the coupling member clockwise. This has the effect of unscrewing the coupling member to the position shown in Figure 1, whereupon the continued operation of the handle effects the continued operation of the stirrer or agitator.

What I claim is:—

1. A combined closure and coupling member for a container having means for engaging an agitator, and a locking ring adapted to secure said member against removal, said locking means having means for engagement with the container and said member.

2. A combined closure and coupling member adapted to be screwed into a threaded aperture in a container and having means for engaging an agitator, and a lock adapted to be located between the container and said member and having lugs for engaging said container and said member.

3. The combination with a container having a threaded opening and an adjacent recess, and an agitator in said container, of a combined coupling member and closure screwable into said opening and engaging said agitator, said coupling member having a recess, and a lock encircling said member and having lugs for projection into said recesses in said coupling member and said container.

4. The combination with a container having a threaded opening and an adjacent recess, and an agitator in said container, of a combined coupling member and closure screwable into said opening and engaging said agitator, and a gasket having means for locking said coupling member to said container to prevent said member from being unscrewed.

5. The combination with a container having a threaded opening and an adjacent recess, and an agitator in said container, of a combined coupling member and closure screwable into said opening and engaging said agitator, a detachable handle for operating said coupling member, and an annulus having means for locking the handle, when detached, and said coupling member to said container.

6. The combination with a container having a threaded opening and an adjacent recess, and an agitator in said container, of a

combined coupling member and closure screwable into said opening and engaging said agitator, a detachable handle for operating said coupling member, and an annulus

5 between the closure and the container and having lugs for engagement therewith, and provided with a clamp for securing the detached handle to said container.

7. A combined coupling member and closure, having a threaded portion to engage a threaded aperture in a container and having a notched head, and a lock adapted to encircle said member and to lie under the head thereof, said lock having lugs adapted 10 to engage said notch and also a recess in the container.

8. The combination with a container having a threaded opening and an adjacent recess, and an agitator in said container, of a 15 combined coupling member and closure screwable into said opening and engaging said agitator, a detachable handle for operating said coupling member, and a locking annulus having lugs adapted to be bent into 20 engagement with the recesses in said container and coupling member and having an extension for securing the detached handle to said container.

9. The combination with a container having a threaded opening and an adjacent recess, and an agitator in said container, of a 25 combined coupling member and closure screwable into said opening and engaging said agitator and having a notched head, and a locking ring adapted to encircle said 30 coupling member and to lie between the head thereof and said container, and having

lugs adapted to be bent into engagement with the said notched head and with the recess of said container.

40 10. The combination with a container having a threaded opening and an adjacent recess, and an agitator in said container, of a combined coupling member and closure screwable into said opening and engaging 45 said agitator and having a notched head, a locking ring adapted to encircle said coupling member and to lie between the head thereof and said container, and having lugs adapted to be bent into engagement with 50 the said notched head and with the recess in said container, a detachable handle for operating said coupling member, and a clamp for securing said handle, when detached, to said container.

55 11. The combination with a container having a threaded opening and an adjacent recess, and an agitator in said container, of a combined coupling member and closure screwable into said opening and engaging 60 said agitator and having a notched head, a locking ring adapted to encircle said coupling member and to lie between the head thereof and said container, and having lugs adapted to be bent into engagement with 65 the said notched head and with the recess in said container, a detachable handle for operating said coupling member, and a clamp for securing said handle, when detached, to said 70 container, said clamp being formed on and projecting from said locking ring.

In testimony whereof I have affixed my signature.

CHARLES E. FARRINGTON.
